TENSION DEVICE

Harold Wood Hitchcock, Apponaug, R. I., assignor
to Universal Winding Company, Boston, Mass.,
a corporation of Massachusetts

Application August 11, 1938, Serial No. 224,386

12 Claims. (CL 242—150)

The present invention relates to improvements in devices for tensioning strand materials such as yarn, thread and the like during their delivery to winding machines or in other transfer processes.

One object of the invention is to provide a tension-device having means for controlling the operation thereof to maintain a more uniform tension on the strand without intermittent fluctuations therein.

Another object of the invention is to provide a tension-device comprising opposed disks adapted to bear against the strand to resist its travel therebetween with means bearing against the rims of the disks to exert a yieldable pressure thereon without permitting the disks to chatter or vibrate.

Another object of the invention is to provide means for sensitively controlling the tension-disks to permit them to respond to irregularities in the resistance to the draft on the strand at its source of supply and to permit the passage of knots, slubs, bunches and enlargements on the strand through the tension-device without causing complete relief of the applied tension or undue fluctuation therein.

Another object of the invention is to provide a tension-device comprising opposed disks having flanged rims with resilient diaphragms bearing against said rims to exert a uniform pressure on the disks.

Another object of the invention is to provide a tension-device comprising opposed disks with means for regulating the pressure on the disks to vary the tension applied to the strand in accordance with the rate of its linear travel.

Another object of the invention is to provide a tension-device having improved pressure-regulating means operated automatically from the winding machine to which the strand delivers.

Another object of the invention is to provide a tension-device of simple structure and arrangement adapted for economical manufacture and proof against derangement and excessive wear during extended periods of operation.

Further objects of the invention are set forth in the following specification which describes, by way of example, several preferred forms of construction of the tension-device and the method of applying it to use as illustrated by the accompanying drawings. In the drawings:

Fig. 1 is a side elevation of a conventional type of winding machine showing the present improved tension-device applied to use therewith and embodying automatically-operated means for

progressively relieving the applied tension as the linear speed of the yarn is increased during the winding operation;

Fig. 2 is an enlarged detail view of one form of the present tension-device shown part-sectional in a plane coincident with the axis of the tension-disks;

Fig. 3 is a perspective view of one of the resilient diaphragms employed for applying pressure to the rims of the tension-disks;

Fig. 4 is a part-sectional view of a modified form of the tension-device embodying a spring for applying pressure to the resilient diaphragms which act against the rims of the tension-disks;

Fig. 5 is a similar view showing weighted means for applying pressure to the diaphragms which act against the tension-disks;

Fig. 6 is a part-sectional view of a still further modified form of construction of the tension-device;

Fig. 7 is a side elevation of the same showing the pressure means as consisting of spider-like springs having radial arms bearing against the rims of the tension-disks; and

Fig. 8 is a perspective view of one of the pressure springs shown in Figs. 6 and 7.

In the present drawings the invention is shown as applied to use with a winding machine of usual construction, but it is to be understood that it may have other uses in connection with textile apparatus of different types employed for various purposes. The present improved tension-device may be employed for applying tension to a yarn feeding at a constant speed or it may be adapted for use in combination with means for applying a varying degree of tension to the strand as its speed of draft is varied during its take-up by the machine.

Fig. 1 of the drawings illustrates a well known type of winding machine comprising a main frame 2 having upper bearings for a rotary winding spindle 3 and lower bearings for a cam-shaft 4. Cylindrical or conical packages may be wound on the spindle 3 by traversing the yarn longitudinally thereof through the means of a thread-guide 5 which is supported on a swinging frame 6 and reciprocated longitudinally of the spindle. The thread-guide 5 is connected to a reciprocatory traverse-rod 7 slidable in grooved bearings in the traverse-frame 6 and actuated from a helical cam, not herein shown, rotated by the cam-shaft 4. The traverse-frame 6 is pivoted on the ends of the cam-shaft 4 to adapt the thread-guide 5 carried thereby to move outwardly away from the winding spindle 3 as the

package is built up thereon. The traverse-frame 6 is counterbalanced by a weighted arm 9 depending from its forward bearing on the cam-shaft 4 whereof to maintain the thread-guide 5 in contact with the surface of the package 5 throughout the winding operation.

The elements above described, as well as certain other parts shown in Fig. 1 of the drawings, are common to winding machines of the present type and will not be further referred to herein except in connection with the means for automatically varying the amount of tension applied to the strand in proportion to its increase in linear speed as the package increases in diameter during the winding operation. Suffice it to state here that it is a common practice to provide means actuated by the movement of the thread-guide away from the winding spindle to gradually and continuously relieve the tension on the strand as its speed of draft increases with the growth in diameter of the package. The present invention contemplates improved means for varying the action of the tension-device for the same purpose and this means will be later described in detail.

Referring to Fig. 2 of the drawings, the present improved tension-device comprises a pair of concavo-convex disks 10 and 11 rotatably mounted on an axial spindle 12 which is herein shown as being of tubular or sleeve-like structure. The tubular spindle 12 is held fixed at one end in a suitable support which, in the present case, is constituted by a hub 13 at the end of a curved arm constructed as a bracket 14, shown in Fig. 1 as fastened to the side of the winding machine frame 2. The spindle 12 may be fixedly secured in the hub 13 by any suitable means such as a set-screw 15 screwed into the hub with its end impinging against the side of the spindle. Extending radially from the hub 13 is a disk-like flange 17 formed with an overhanging annular rim 18 which partly encloses the tension-disk 10 in the manner of a hood.

The tension-disks 10 and 11 are preferably constructed from sheet-metal and formed to substantially saucer shape with their main radial portions having flat faces adapted to bear against the strand's drawing therebetween. Radially outward beyond the flat portions of the tension-disks they are flared laterally in arcuate shape in cross-section and terminate in radial flanges forming flat rims 20 and 21 substantially parallel with their main flat faces.

The means for applying pressure to the disks to force them toward each other to bear against the strand consists in a flexible diaphragm 25 for each disk constructed from suitable resilient material such as rubber, fiber or the like. The diaphragms 25 are of disk-like form, as shown in Fig. 3, and of substantially the same outside diameter as the tension-disks 10 and 11 to adapt them to bear against the rims 20 and 21 of the latter in the manner illustrated in Fig. 2. The diaphragms 25 are formed with axial holes 26 to adapt them to be supported on the central spindle 12 and pressure is applied to the sides of the diaphragms adjacent their centers to cause them to yieldingly press against the outer rims 20 and 21 of the disks 10 and 11.

As shown in Figs. 1 and 2, a preferred form of construction of the pressure means comprises a plunger-pin 27 which is slidable in the axial bore of the hollow spindle 12 and carries a tubular hub or thimble 28 at its outer end for engaging the side of the outer disk 25. The inner disk 25 has its central portion bearing against a relatively

thin washer 29 abutting the end of the hub 13 in which the spindle 12 is held. The thimble 28 is bored axially at 30 to receive the end of the spindle 12 to adapt it to slide thereon and is secured to the plunger-pin 27 by suitable means such as a set-screw 31. It will thus be observed that when the plunger-pin 27 is slid to the left as viewed in Fig. 2 the thimble 28 will bear against the central portion of the outer diaphragm 25 to exert pressure on both diaphragms whereof to cause them to yieldingly press against the rims 20 and 21 of the two disks 10 and 11. As the pressure of the thimble is increased the diaphragms will be flexed to cause them to be bowed inwardly toward each other to a slight extent.

Any suitable means may be employed for sliding the plunger-pin 27 through the bore of the spindle 12 and, as illustrated in Figs. 1 and 2 of the present drawings, a rockable lever 33 is provided for this purpose. The lever 33 is pivoted on a screw or stud 34 screwed into a bearing 35 on an arm 36 projecting upwardly from the mounting 13 for the spindle 12 and formed integrally with the arm or bracket 14. At the lower end of the lever 33 is a slot 37 into which the bent end 38 of the plunger-pin 27 is hooked. In the embodiment of the invention as shown in Figs. 1 and 2, means are provided for rocking the lever 33 to slide the plunger-pin 27 to vary the amount of pressure applied by the thimble 28 to flex the diaphragms 25. That is to say, where a differential or varying degree of tension is to be applied to the strand in accordance with its changing linear speed during its feed to the winding package the lever 33 is rocked continuously during the winding operation to slide the plunger-pin 27 to the right as viewed in Fig. 2 whereof to relieve the pressure on the diaphragms 25.

As shown in Fig. 1 the means for rocking the lever 33 includes a weighted lever 40 connected to the counterweighted arm 9 of the traverse-frame 6 to adapt it to be actuated therefrom as the thread-guide 5 swings outwardly away from the winding spindle 3. It has before been proposed in the present art to employ weighted levers rocked on their pivots by the swinging movement of the traverse-frame to vary both the pressure of the thread-guide against the package and the degree of tension applied to the running yarn or thread. Heretofore, however, one lever usually has been pivoted directly to the frame 2 of the machine for applying pressure to the thread-guide and a second lever pivoted on the first lever and connected to control the tension-device. In the present improved form of construction the pressure lever and tension-lever are mounted separately and separately connected to the traverse-frame 6 to adapt them to act independently of each other and to be adjusted individually. As illustrated in Fig. 1, a pressure lever 41 is pivoted on a stud 42 screwed into the side of the arm or bracket 14 which is fast on the main frame 2 of the machine. A rod 43 connected at 44 to the pressure lever 41 has its opposite bent end hooked into one of a series of notches 45 in an adjusting element or plate 46 fastened to the weighted arm 9 of the traverse-frame 6. The pressure lever 41 carries a slidable weight 47 which may be adjusted toward and away from its fulcrum to vary the amount of resistance which the lever applies to the swinging movement of the traverse-frame 6. By adjusting the rod 43 in the different notches 45 the extent of upward swinging movement of the lever 41 can be regulated, it being apparent that as the

pressure lever swings upward during the movement of the traverse-frame 6 as the thread-guide 5 recedes from the axis of the package during the growth in diameter thereof the effect of the weight 47 will be lessened to relieve the pressure of the guide on the package. The arrangement of the pressure lever and its method of action are the same substantially as previously employed in the present art. In the present preferred form of construction of the tension-device, however, the tension-lever 40 is mounted independently of the pressure lever 41 to adapt it to be adjusted and actuated independently thereof. Pivoted on the stud 42 at the forward side of the lever 41 is a shorter elbow-shaped lever 48. Pivotedally connected to the vertical arm of the elbow-shaped lever 48 is a rod 49 having its opposite hooked end engaged with one of a series of holes 51 in the adjusting member or plate 46 carried by the arm 9 of the traverse-frame 6. The forward end of the rod 49 has a right-angled portion 50 hooked through the lever 48 with its end serving as a pivot bearing for the tension-lever 40 mounted thereon. The pivoted end of the tension lever 40 is of quadrant shape having an arcuate slot 52 formed therein. At the rear of this portion of the tension lever 40 is another angularly shaped lever 53 having one of its arms pivoted on the bent end of the rod 49. A screw 54 passing through the slot 52 in the lever 40 is screwed into the lever 53 to provide means for adjusting the tension-lever in angular relation to the latter. The angular lever 53 is connected at its upper end at 55 to a rod 56 which has its opposite end hooked through a hole 57 in the lever 33. Preferably, the lever 33 has a series of holes 57 for adjustably connecting the lever 52 therewith to regulate its action on the pressure means of the tension-device.

Arranged below the tension-device is a wire guide 60 supported from the bracket 14 and disposed in position to guide the strand *s* between the opposed faces of the tension-disks 10 and 11. The strand *s* is drawn upwardly from the tension-device over a guiding pin or rod 61 and thence leads across a thread-bail 3 on the traverse-frame 6 to direct it through a groove in the thread-guide 5. The end of the strand of yarn or the like is attached to a paper cop-tube *x* or other yarn-carrier or core for the package and when the machine is started to operate the yarn is wound thereon to build up a package of overlying layers composed of helical coils deposited by the reciprocating thread-guide 5. As the winding package increases in diameter the thread-guide 5 is forced outwardly away from the spindle 3, thereby causing the traverse-frame 6 to rock outwardly or in a clockwise direction as viewed in Fig. 1. The lower weighted arm 8 of the traverse-frame is thus caused to swing rearwardly away from the tension-device and during this movement the rod 43 connected thereto will rock the pressure lever 41 upwardly to alter its leverage whereof to relieve the pressure of the thread-guide 5 against the package. At the same time the rod 49, also connected to the arm 8 of the traverse-frame, will rock the elbow-shaped lever 48 in the same direction, or clockwise, to displace the pivot 58 of the tension-lever 40 toward the left. The displacement of the pivot 58 of the tension-lever 40 causes the latter to be rocked upwardly to reduce its leverage and thereby its pressure on the rod 56, which is connected between the angular lever 53 and the lever 33, is reduced. As the pressure or force

tending to rock the lever 33 to the left, as viewed in Fig. 1, is decreased its pressure on the plunger-pin 27 is likewise relieved so that less pressure is exerted by the thimble 28 against the side of the outer diaphragm 25. In this way the pressure of the two diaphragms on the tension-disks 10 and 11 is reduced so that the disks will bear less firmly against the strand s drawing therebetween whereof to reduce the tension applied to the yarn. It will be understood that this relief of the pressure on the diaphragms and the corresponding decrease in the pressure of the tension-disks against the strand is effected gradually and continuously from start to finish of the winding of each package and in proportion to the increase in linear speed of the strand as it feeds to the winding. Stated another way, as the speed of draft of the yarn increases due to the growing diameter of the package being wound the applied tension on the yarn is gradually relieved so that the ultimate tension remains substantially constant or uniform throughout the winding.

As the strand passes rapidly between the two tension-disks 10 and 11 at one side of the spindle 12 it has a tendency to rotate the disks and this rotative action is resisted to a slight extent by the pressure of the thimble 28 and the washer 29 against the sides of the diaphragms 25. However, the rapid draft of the strand is sufficient to rotate the disks slowly with a sort of creeping action whereby new surface is continuously presented to the running strand to prevent wearing grooves in the faces of the disks. With the present improved construction and arrangement of the tension-device and the means for varying the pressure on the tension-disks the strand is delivered to the winding machine or other apparatus under substantially uniform tension during the variation in its linear speed. That is to say, where normally the increase in linear speed of the yarn would increase the frictional effect of the tension-disks thereon, by relieving the pressure on the tension-disks in proportion to the increasing speed of draft of the yarn the applied tension is relieved to compensate for the increase in linear speed of the yarn. The engagement of the diaphragms 25 with the disks at a distance from their axis maintains the disks in substantial parallelism while permitting them to separate to permit the passage of knots, slubs, bunches or other enlargements on the strand. On the other hand, this novel arrangement for applying the pressure at the outer rims of the disks has the effect to prevent them from rocking or canting to set up vibration or chattering which would cause fluctuations in the tension applied to the strand.

While the present tension-device is particularly well adapted for use as above described it may also be employed to advantage in applying tension to a strand feeding at a constant rate. In such case the means for applying pressure to the flexible diaphragms 25 may consist of a spring or weights as illustrated in Figs. 4 and 5 of the drawings. In Fig. 4 the tension-disks 10 and 11 are shown as mounted on a fixed spindle 62 with the washer 29 at the side of the inner diaphragm 25 and another washer 63 bearing against the outer diaphragm 25. A helical wire spring 65 surrounding the spindle 62 has one end engaged with the washer 63 and is held under compression by a collar 66 which is adjustable longitudinally of the spindle 62 and secured in place by a set-screw 67. By adjusting the position of the collar 66 the tension of

the spring 65 may be regulated to apply the proper amount of pressure on the diaphragms 25 whereby to secure the required degree of tension on the strand feeding between the disks 10 and 11. It will be understood that the diaphragm 25 operate in the manner as previously explained to exert a yieldable pressure on the tension-disks while permitting them to turn slowly or creep rotatively due to the draft of the strand across their opposed faces.

Fig. 5 illustrates substantially the same arrangement of the tension-disks and diaphragms 25 except that the spindle 68 is disposed vertically and weights 70 applied to its upper end to serve as pressure means for the diaphragms. The weights 70 may be of disk-like form slideable on the spindle 68 to rest upon a small washer 71 which bears against the upper diaphragm 25. In this case the device operates in the same manner as that shown in Fig. 4 with the diaphragms bearing against the rims 20 and 21 of the disks 10 and 11 to cause them to press against the strand s drawing therebetween.

Figs. 6, 7 and 8 of the drawings illustrate a still further modified form of construction of the means for applying pressure to the tension-disks. In these latter views the tension-device is illustrated in substantially the same form as shown in Fig. 2 with the tension-disks 10 and 11 mounted on a tubular spindle 12 held in the hub 13 of the bracket 14. In place of the rubber or fiber diaphragms 25, however, resilient springs of spider-like shape are arranged to bear against the rims 20 and 21 of the disks 10 and 11. As shown most clearly in Figs. 7 and 8, the springs 75 are constructed of relatively thin sheet-metal and preferably tempered to give them proper resilient action. Each spring 75 is formed with an annular hub portion 76 and a plurality of arms 77 radiating therefrom in angularly spaced relationship. Preferably, the springs 75 have three equidistantly spaced arms, but a greater number may be provided in some instances. The hubs 76 of the springs 75 are formed with central apertures 78 for receiving the axial spindle 12 and the arms 77 are dimensioned to adapt their ends to bear against the flanged portions 20 and 21 of the disks 10 and 11 as shown in Fig. 6. A felt or other type of cushion washer 80 is arranged in abutting relationship with the end of the hub 13 and bears against the hub 76 of the inner spring 75, while the hub of the outer spring 75 is engaged by the end of the thimble 28 which is fast on the end of the plunger-pin 27. Pressure is applied to the springs 75 to force the tension-disks 10 and 11 toward each other by sliding the plunger-pin 27 as, for example, by the action of the lever 33 described with reference to Figs. 1 and 2.

With this latter form of construction of the tension-device it has been found that there is a tendency for the tension-disks to spin or rotate rapidly under the draft on the yarn, due to the fact that the bearings of the disks and the springs 75 on the spindle 12 are of relatively small dimensions and substantially frictionless. Therefore, it has been found preferable to prevent rotation of the springs 75 so that their frictional engagement with the rims of the disks 10 and 11 will have the effect to retard the 70 rotational movement of the disks. That is to say, the frictional engagement between the ends of the arms 77 of the springs and the rims 20 and 21 of the disks 10 and 11 will provide a braking force so that the disks will rotate slow-

ly or creep. Any convenient means may be provided for preventing rotation of the springs 75 and, as illustrated in Figs. 6 and 7, a pin or stud 81 is screwed into the side of the flange 17 of the hub 13 with its end projecting into engagement with one of the arms 77 of the spring 75. To hold the outer spring 75 from rotative movement a wire ring 82 formed to snap into a groove 83 in the thimble 28 is provided with a right-angular leg 84 at one end which projects into position to engage one of the arms 77 of the spring.

With the tension-device constructed in the form as last described its method of operation is substantially the same as first explained, pressure being applied to the central portions or hubs 76 of the springs 75 to cause the extremities of their arms 77 to bear against the flanged rims 20 and 21 of the tension-disks 10 and 11 to yieldably press the disks against the strand s. The pressure of the springs 75 is adjusted by regulating the force applied to the plunger-pin 27 to urge the thimble 28 against the outer spring 75, and with the maximum pressure applied the springs will be bowed inwardly toward each other while their arms 77 act resiliently to adapt them to yield when the tension-disks are forced apart by the passage of a knot, bunch or other enlargement on the strand s. This last-described modified form of construction of the tension-device is particularly well adapted for use in tensioning yarns which have been moistened or emulsified as the liquid is apt to deteriorate the rubber diaphragms employed with the previously-described embodiment.

It will be observed from the foregoing that the present invention provides an improved tension-device having novel means for applying pressure to one or a pair of tension-elements to cause the latter to bear against a running strand to apply a uniform tension thereto. The improvement is particularly adapted for use with a tension-device comprising opposed disks between which the strand feeds and the pressure means may comprise resilient diaphragms, springs or the like bearing against the rims of the disks; or in other cases, a single disk may be used arranged in opposed relation to a fixed member across which the strand draws and with the resilient diaphragm or spring acting on the single disk. Due to the present novel arrangement for applying the pressure at the outer rim of the disk or disks the latter will be restrained from excessive rocking or canting motion and thus prevented from chattering or vibrating to cause fluctuations in the tension applied to the strand. The present invention also provides improved means for automatically varying the force of the pressure means to adjust the amount of tension applied to the strand in accordance with changes in its linear speed of draft whereby to maintain a more uniform and constant ultimate tension on the strand.

While the present improved tension-device is herein shown and described as embodied in several preferred forms of construction, it is to be understood that other modifications may be made in the structure and arrangement of its parts without departing from the spirit or scope of the invention. Therefore, without limiting myself in this respect, I claim:

1. A tension-device comprising opposed tension-disks having contact faces adapted to bear against a strand feeding therebetween and flaring peripheral rims, and resilient elements bear-

ing directly against the peripheral rims of the said disks to press them against the strand.

2. A tension-device comprising opposed disk-like members having relatively flat faces adapted to bear against a strand drawing therebetween and flaring peripheral rims, resilient means bearing directly against the peripheral rims of the disks, and means bearing against said resilient means at points adjacent the axes of the disks to apply pressure to force the disks toward each other. 10

3. A tension-device comprising a central spindle, tension-disks rotatably mounted on said spindle in opposed relationship to adapt them to bear against a strand feeding therebetween said tension-disks having flaring rims at their outer peripheries, and resilient means bearing against the outer rims of the disks to apply pressure thereto to press the disks against the strand. 15

4. A tension-device comprising a spindle, a pair of concavo-convex disks rotatably mounted on said spindle, a pair of resilient diaphragms arranged with their outer portions bearing against the peripheral rims of the disks, and means to apply pressure to the central portions 20 of said diaphragms. 25

5. A tension-device comprising disks adapted to bear against a strand drawing therebetween and having flaring peripheral rims, and resilient elements having a central portion and arms radiating therefrom with their ends engaging directly against the outer edges of the peripheral rims of the disks to apply pressure thereto. 30

6. A tension-device comprising a spindle, a disk mounted rotatably on said spindle and adapted to bear against a strand drawing thereacross, said disk having a flaring rim at its outer periphery, resilient means bearing against the rim of the disk, a plunger slidably axially of said disk, and means on said plunger engaging the resilient means adjacent the axis of the disk to cause the resilient means to flex as it bears against the outer rim of the disk. 35

7. A tension-device comprising a tubular spindle, a tension-disk rotatably and slidably mounted on the spindle to adapt it to bear against a strand drawing thereacross, a resilient diaphragm supported on the spindle with its outer rim bearing against the outer rim of the disk, a plunger slidable through the bore of the spindle, and an abutment on the end of the plunger adapted to bear against the diaphragm to flex the latter to apply pressure against the rim of the disk. 50

8. A tension-device comprising a hollow spindle, a pair of disks rotatably mounted on said spindle, a pair of resilient diaphragms supported on the spindle with their outer portions bearing against the outer rims of the disks, a fixed abutment engaging one of the diaphragms adjacent its center, a plunger-pin slidable through the bore of the spindle, and an abutment on the 55 60

plunger-pin adapted to bear against the other diaphragm adjacent the center thereof.

9. A tension-device comprising a hollow spindle, a pair of concavo-convex disks rotatably and slidably mounted on said spindle, a pair of resilient diaphragms supported from the spindle with their outer portions in engagement with the flaring rims of the disks, fixed means bearing against the central portion of one of said diaphragms, a plunger slidable through the bore of the spindle, means on said plunger bearing against the central portion of the other diaphragm, and a weighted lever connected to slide the plunger to flex the diaphragms to apply pressure to the rims of the disks. 10

10. In combination with the winding spindle and thread-guide of a winding machine adapted to recede one from the other during the growth in the winding, a tension-device comprising a disk adapted to bear against the strand feeding to the winding spindle and having a flaring rim at its outer periphery, a flexible element arranged to bear against the outer rim of the disk, means for applying pressure to said element adjacent the axial center thereof, and means actuated by and with the separation of the winding spindle and thread-guide to move said pressure means to reduce the pressure of the resilient element against the rim of the tension-disk. 15

11. In combination with the winding spindle and thread-guide of a winding machine adapted to recede one from the other with the growth in the winding, a weighted lever, means for rocking the lever during the separation of the winding spindle and thread-guide, a tension-device comprising a pair of opposed disks adapted to bear against the strand feeding to the winding spindle and having flaring rims at their outer peripheries, resilient elements arranged to bear solely against the rims of said tension-disks, and means actuated by the lever for applying pressure against the central portion of one of the resilient elements to cause the latter to bear against the rim of one tension-disk with a variable pressure thereon as the tension-lever is rocked during the winding of a package. 20

12. A tension-device comprising a tubular mounting, a pair of tension-disks supported concentrically of the mounting and adapted to bear against a strand drawing therebetween, said tension-disks having flaring rims at their outer peripheries, resilient diaphragms bearing against the flaring rims of the tension-members, a plunger-pin slidable in the tubular mounting, and an abutment on the end of the plunger adapted to bear against one of the diaphragms to flex the latter to apply pressure against the rim of the disk on which it bears. 25

HAROLD WOOD HITCHCOCK.
